UNITED STATES PATENT OFFICE.

WILLIAM HEATON LONGSDORF, OF LONDON, ENGLAND.

FURNACE FOR STEAM-GENERATORS OR THE LIKE.

SPECIFICATION forming part of Letters Patent No. 767,704, dated August 16, 1904.

Application filed November 28, 1903. Serial No. 183,076. (No model.)

To all whom it may concern:

Be it known that I, WILLIAM HEATON LONGSDORF, a citizen of the United States, residing in London, England, have invented certain new and useful Improvements in Furnaces for Steam-Generators or the Like, of which the following is a specification.

This invention relates to the class of furnaces wherein steam is admitted to the fire-box to enhance combustion; and the object of the invention is to provide means for superheating the steam to a point near that of decomposition before it is admitted to the bed of fuel in the fire-box and to provide a distributing-head for the steam of special form and adapted to eject the steam in jets to the desired points in the fire-box.

In the accompanying drawings, which serve to illustrate an embodiment of the invention as applied to the furnace of a boiler of the Lancashire type, Figure 1 is a longitudinal vertical section through the axis of a furnace-flue and a part of the boiler, the furnace being equipped with this invention. Fig. 2 is a front elevation. Fig. 3 is a transverse vertical section taken at line x^3 in Fig. 1 and looking toward the front. Figs. 4 and 5 are detail views of the superheater on a larger scale than the principal views, Fig 4 being a section along line x^4 in Fig. 5 and Fig. 5 being a plan broken away along the line x^5 in Fig. 4. Figs. 6 and 7 are respectively an elevation and plan of a form of the distributing-head differing somewhat in shape from the head shown in the principal views. Fig. 8 is a sectional view showing a slightly modified arrangement of the conduit in the superheater.

In the efforts heretofore made to superheat steam to be supplied to a furnace above the fire-bed, and especially in the class of internal furnaces, such as those employed in the Lancashire and Scotch boilers, great difficulty has been experienced in raising the temperature of the steam sufficiently for admission to the furnace with good effect and also in providing a superheater which could be maintained intact under the intense heat. In providing such a boiler with means for superheating and delivering steam to the fire-box it is essential that the means employed shall be simple in

construction and durable. The present invention has for its object to overcome these difficulties as well as to improve the construction in other respects. Usually the Lancashire boiler has in it two symmetrically-arranged 55 furnace-flues, each provided with a furnace; but as the furnaces are alike only one of the furnace-flues is shown in the drawings.

1 designates the boiler; 2, the furnace-flue therein; 3, the fire-box; 4, rotatable grate-bars 60 of a known kind; 5, the bridge-wall; 6, the charging-opening, and 7 the front plate or head of the boiler. These are known features, and the present invention is not restricted to the use of this special kind or construction of 65 the devices named.

About the charging door or opening 6 and forming, as herein shown, the frame for said opening is a superheater 8, which is connected by a pipe 9 with the steam-space in the boiler 70 1 or with any other course of supply which will furnish steam. As shown in the detail views, Figs. 4 and 5, this superheater 8 is in the form of an arch with uprights at its sides. It will be made of metal, preferably iron or 75 steel, and will have formed in it a zigzag passage 8^a for the steam. The pipe 9 connects with the superheater at one end of the zigzag passage or conduit, and from the other end thereof a pipe 10 conveys the superheated 80 steam to a distributing-head 11 within the fire-box and secured to the front 7 above the superheater.

As shown in the principal views, the distributing-head has a rectangular form when 85 seen from the point of view of Fig. 3 and a somewhat triangular form when seen from the point of view of Fig. 1, the inner face thereof, which is presented toward the bridge-wall, being rounded or convex and provided with 90 several tiers or rows of perforations or jet-apertures 12 to emit jets of highly-superheated or gaseous steam into the fire-box. The jet-apertures of the several tiers are disposed at different vertical angles, as indicated by the 95 dotted lines extending therefrom in Fig. 1, in order to distribute the gaseous fluid to all parts of the bed of fuel. This distributing-head may have the form shown in Figs. 6 and 7, where the head 11^a has the form of half the 100

frustum of a cone and the jet-apertures therein are so disposed as to direct the jets divergently at horizontal as well as vertical angles.

The steam before it enters the fire-box from the jet-apertures must be raised to a temperature of not less than 650° Fahrenheit in order to produce the best effective results, and this temperature will be attained in its flow through the zigzag or serpentine conduit 8^a in the superheater and in the distributing-head.

The superheater 8^x (shown somewhat diagrammatically in Fig. 8) differs from that already described only in providing a longer zigzag conduit for the steam and in having both the inlet and outlet for steam at its top or crown. In this disposition of the conduit the passage extends twice the length of the superheater.

It will be noted that the distributing-head according to this invention is somewhat triangular in vertical section, as seen in Fig. 1, its base projecting out from the inner face of the fire-box front and its apertured face inclined and directed obliquely upward, and that the superheater extends out underneath its projecting base so as to protect the head from the fierce heat of the furnace, the face thereof being protected by its inclination.

Having thus described my invention, I claim—

1. A furnace for the purpose specified, having at its front a superheater 8, which extends about the charging door or opening 6, said superheater having in it a zigzag conduit 35 8^a for the steam, means for introducing steam to said passage at one end thereof, a distributing-head 11, in the fire-box above said superheater and provided with jet-apertures 12 in its face which is presented toward the back 40 of the fire-box, and a pipe connecting the conduit in the superheater with said head.

2. A boiler-furnace, having means for supplying steam in jets to the fire-box, having a frame for the charging-opening provided interiorly with a zigzag passage for steam whereby it forms a superheater, having means for supplying steam from the boiler to said superheater, and means connecting said superheater with the jet device.

In witness whereof I have hereunto signed my name, this 23d day of November, 1903, in the presence of two subscribing witnesses.

WILLIAM HEATON LONGSDORF.
